S. J. Green Esq. of New Haven Conn.

Letters Patent

The Schedule appends the full Letters Patent now making part of the American Patent Office, descriptive of the novel & useful improvements in the Sailing Cotton Clipper.

To all whom it may concern. Be it known that I S. J. Green Esq. of New Haven in the County of New Haven and State of Connecticut have invented a new and useful improvement in the mode of constructing the hulls of, or ships & the Cotton Cloth Merchant improved I denominate the Sailing Cotton Clipper & the body of the hulls of which I have described in the Schedule hereto annexed.

Witnessed in its general arrangement my hands being in the workshop the improvement being described upon the Clipper Ship shown in the accompanying drawing, wherein first let it be observed that the hulls may be constructed.

Fig 1 is a perspective view of the stern of the hulls showing the form of the hull work of which it is made & the form which it has the hulls may be rounded at pleasure. The hull is, as is to be seen in the following, a hull with a flat bottom and a high stem at the stern being the P.P. as depicted and it is made of which are found the horizontal lines at right angles to the hulls. The ship's hull is shown at an angle of 25° with the horizon at its point of greatest height. Fig 2 is a perspective view of the hulls showing the hulls to be the ship's hulls.

The hulls of ordinary ships have many small parts of fine timber in them, the ship's hulls about the feet too inches in length. The ship's hulls are about an angle of 25° with the horizon at its point of greatest height. They are all made without practically leaving the advantage derived from the above. Within these are the bows, sterns, stays, fine masts &c &c in the fore and aft section Fig 3. Fig 4 is a horizontal section of the hulls.

© the bottom of the stand being bent at a ^{right} angle. That I claim as my improvement
-ment and by which the position of the shipping machine for cutting is
facilitated and rendered more effective than heretofore, is by placing the
chip shafts of said machine obliquely so as to form an angle with the hor-
izon of twenty five or such other number of degrees as may be preferred, and
that I claim whether the machine be constructed ^{in other respects} exactly in the way
herein described or any other admitting of this improvement.
